Specification for Design.

Patented Sept. 22, 1914.

Application filed June 10, 1914. Serial No. 844,380. Term of patent 14 years.

To all whom it may concern:

Be it known that I, CHARLES H. TRUE, a citizen of the United States, residing at Hammond, Lake county, Indiana, have invented a new, original, and ornamental Design for a Casting-Die for Grinding-Tools, of which the following is a specification, reference being had to the accompanying drawing, forming a part thereof.

The figure is a perspective view of a die showing my new design.

I claim:

The ornamental design for a casting die for grinding tools, as shown.

In testimony whereof I have hereunto set my hand in the presence of two subscribing witnesses.

CHARLES H. TRUE.
